Frederick Sholes INVENTOR:
BY

H. G. Burns ATTORNEY.

UNITED STATES PATENT OFFICE.

FREDERICK SHOLES, OF CHICAGO, ILLINOIS, ASSIGNOR TO MORLEY MULTIPLE TYPE-WRITER SALES CORPORATION, A CORPORATION OF INDIANA.

DUAL TYPEWRITING MACHINE.

Application filed February 23, 1922. Serial No. 538,439.

To all whom it may concern:

Be it known that I, FREDERICK SHOLES, a citizen of the United States of America, and resident of Chicago, in the county of Cook 5 and State of Illinois, have invented certain new and useful Improvements in Dual Typewriting Machines, of which the following is a specification.

This invention relates to improvements in 10 dual typewriting machines of that class in which more than one set of type-bars are actuated by a single set of keys. The objects of the invention are: first, to provide a simple and compact mechanism for transmitting movement from the keys to both 15 sets of type-bars; second, to provide a means of conveniently disconnecting one set of type-bars from actuated relation with the keys; and third, to provide a means of 20 automatically increasing the tension applied to the universal bar that co-operates with the key-bars, when the one set of type-bars are disengaged from operating connection.

The above objects are accomplished by 25 the construction illustrated in the accompanying drawings in which:—

Fig. 1 is a front elevation of a dual typewriter embodying the present invention, a portion being broken away, and other parts 30 immaterial to the present invention being omitted;

Fig. 2 is a plan view of the grouped rocking members that constitute means for transmitting movement from the key-bars 35 to the type-bars of both sets;

Fig. 3 is a vertical section of Fig. 1 on the line 3—3 thereof;

Fig. 4 is a rear elevation of the secondary or duplicating part of the machine;

Fig. 5 is a detail in perspective showing 40 a single unit including dual type-bars, the key-bar for same and the mechanism for transmitting movement from the key-bar to the type-bars, also the mechanism for disconnecting one of the type-bars from actuated relation with the key-bar, parts being broken away;

Fig. 6 is a detail view showing a side elevation of the detachable connection between 45 one of the secondary intermediate levers and its connecting rod, parts being in section; and

Fig. 7 is a plan view showing the head of

the detachable connecting rod, and the intermediate lever, the lever being in section 55 at the point of its connection in the head of the connecting rod.

The characters appearing in the description refer to parts shown in the drawings and designated thereon by corresponding 60 characters.

The invention comprises a master typewriting machine 1 and a secondary typewriting machine 2, each having a set of type-bars 3 and 4 respectively, that operate 65 in conjunction with corresponding platens 5—6. The mechanism constituting the two typewriting machines is assembled in a common frame 7 having a pair of horizontal rails 8 for the support of a carriage 70 9, there being rollers 10 on the carriage that have bearing relation with the rails. The platens are mounted in the front portion 11 of the carriage that is hinged as indicated at 12, and a rail 13 on the hinged portion rests 75 upon a roller 14 on the frame to receive support at its front. The movement of the carriage is controlled by escapement mechanism 15 which may be of any suitable type.

The master machine has a group of key-bars or levers 16 each of which is sustained by a corresponding spring 17 and is adapted to depress the universal bar 19 that is pivoted in the frame beneath the group of key-bars. The universal bar is sustained 85 by a tension spring 20 that depends from a bell-crank 21 which is pivoted in the frame and has actuated relation with an adjusting bar 22.

Each key-bar 16 has a link connection 23 90 with an arm 24 on a corresponding rock-shaft 25 by which oscillating movement is imparted to the rock-shaft when the key-bar is actuated. Each rock-shaft has another arm 26 extending at an angle from 95 the former arm 24, which has a link connection 27 with a corresponding intermediate lever 28 that has pivotal support at its lower end in the frame. Also each type-bar 3 has a link connection 29 with the 100 corresponding intermediate lever 28, so that as the various key-bars are manipulated the type-bars will be accordingly actuated.

A special feature of the invention consists of the rock-shafts 25 and the manner 105 in which they are arranged. These rock-

shafts are in groups of various lengths, the group 30 being the shortest and positioned horizontally in a vertical series and the group 31 being longer and positioned adjacent to the first group, while each succeeding group is of greater length than the preceding group as shown in Fig. 2. The rock-shafts thus grouped are held in position by suitable brackets 32 that extend from a supporting bar 33 in the frame. Except as to length the rock-shaft members 25 are alike, each having an arm 34 at its end opposite its angular arms 24 and 26.

The arm 34 of each rock-shaft has a latch connection 35 with a corresponding intermediate lever 36 in the secondary machine by which movement is imparted to the intermediate lever when the corresponding key of the master machine is manipulated, the movement being imparted through the medium of the rock-shaft 25. Each latch connection has an elongated loop 37 through which the intermediate lever 36 loosely extends, and the lever has a jaw 38 adapted to have engagement with a latch-pin 39 in the looped head of the connection 35 so that when thus engaged the connection and lever will be actuated together. The intermediate lever 36 has also a link connection 40 with the corresponding type-bar 4 of the secondary machine by which the type-bar is actuated.

As a means of throwing the latch connections 35 out of engagement with their intermediate levers, a guide, consisting of a movable bar 41 and rod 42 arranged in parallel relation with each other and spaced apart, is positioned so that the looped ends 37 of the connections 35 extend loosely between the bar and the rod. The rod 42 extends through pendant ears 43 on the bar 41 and the ends of the rod are bent to form arms 44 which are connected respectively with actuating arms 45 that extend from an oscillating shaft 46 that is mounted in the frame. The shaft 46 also has a pendant arm 47 which may be a continuation of one of the arms 45, the pendant arm being connected with the adjusting bar 22. A stop 48 on the frame is positioned so as to limit movement of the shaft 46 in one direction by engaging one of the arms 45 at which time the heads on the connections 35 are held in latched connection with the corresponding intermediate levers by the guide. Tension spring 49 connecting the shaft 46 with the corresponding ears 43 on the bar tend to hold the guide in normal position. By manipulating the adjusting bar 22 the shaft 46 may be oscillated so that the guide will be elevated sufficiently to lift the latch connections 35 from engagement with their intermediate levers. In this manner the type-bars 4 of the secondary machine are rendered inoperative.

The adjusting bar 22 is longitudinally movable and is provided with a pin 50 for engagement in holes 51 in the frame of the machine for holding the lever in its opposite positions of adjustment.

In the operation of the invention the paper to be written upon is applied in a separate sheet to each platen in the ordinary manner, and while the adjusting bar 22 is in its outermost position, the key-bars 75 of the master machine are manipulated as in the operation of an ordinary typewriter. As the movements of the key-bars are imparted to the type-bars of both the master and secondary machines, the manuscript is 80 simultaneously imprinted on the sheets carried by the platens.

If it be desired to produce but one manuscript, the master machine may be operated separately by shifting the adjusting bar 22 85 to its innermost position so that the type-bars of the secondary machine are rendered inoperative while the type-bars of the master machine remain operative. Also, when the adjusting bar is shifted to its innermost 90 position the bell-crank 21 is accordingly moved thereby and the tension of the spring 20 is increased and the resistance of the universal bar 19 to the action of the key-bars thus becomes greater. In this manner is 95 compensated the decrease of force required in operating the key-bars when the type-bars of the secondary machine are disconnected, and thus, "the touch" of the keys of the master machine is preserved when the secondary machine is thrown out of action.

What I claim is:

1. In dual typewriting apparatus having master and secondary sets of type-bars and corresponding platens, a single set of key-bars; a set of rock-shafts grouped together in a loose pack, each having at one end a pair of arms and at its opposite end a single arm; a link connection between each key-bar and one of said pair of arms of the corresponding rock-shaft; a group of intermediate levers having actuating relation with the master set of type-bars; a link connection between each of said levers and the other arm of said pair of arms of the corresponding rock-shaft; a secondary group of intermediate levers having actuating relation respectively with the secondary set of type-bars; a latch connection between the single arm of each rock-shaft and the corresponding lever of the secondary group; a movable guide for said latch connections adapted to collectively disengage the same from actuating relation with the secondary levers; adjusting means controlling the guide; a universal bar depressible by said key-bars; and a tension device having sustaining relation with the universal bar and connection with said adjusting means by which the sustaining tension of said device

is increased when the latch connections are disengaged.

2. In dual typewriting apparatus having master and secondary sets of type-bars and corresponding platens co-operative therewith, a single set of key-bars having actuating relation with the master set of type-bars; a set of rock-shafts grouped together in a loose pack, having actuated relation respectively with said key-bars and actuating relation respectively with the type-bars of the secondary set; adjusting means for collectively disengaging the type-bars of the secondary set from actuating relation with the rock-shafts; a universal bar depressible by said key-bars; and a tension device having sustaining relation with the universal bar and connection with said adjusting means by which the sustaining tension of said device is increased when the secondary set of type-bars are thrown out of action.

3. In dual typewriting apparatus having master and secondary sets of type-bars and corresponding platens co-operatively associated therewith, a set of rock-shafts grouped together in a loose pack having actuating relation respectively with the corresponding type-bars of both the master and secondary sets; said type-bars of the secondary set and rock-shafts being detachably connected; a set of key-bars having actuating relation respectively with the corresponding rock-shafts; and a tension device for the key-bars

operable to increase its tension when said secondary type-bars are detached.

4. In dual typewriting apparatus having master and secondary sets of type-bars and corresponding platens co-operatively associated therewith, a set of key-bars; mechanism having actuated relation with the respective key-bars and corresponding connections with the respective type-bars of the master and secondary sets for actuating the same, the connections with the type-bars of the secondary set being detachable; a tension mechanism depressible by the key-bars; and an adjusting means adapted to collectively disengage the detachable connections and having adjusting relation with said tension mechanism so arranged that the sustaining tension thereof is increased simultaneously with the disengagement of said connections.

5. In dual typewriting apparatus having two sets of type-bars operated by a single set of keys, an adjusting means for collectively throwing one set of type-bars out of action; a universal bar depressible by the key-bars; a tension device for sustaining the universal bar; and a connection between said adjusting means and tension device adapted to increase the sustaining tension of said device when said one set of type-bars are thrown out of action.

In testimony whereof I affix my signature.

FREDERICK SHOLES.
